UNITED STATES PATENT OFFICE.

HARRY H. KEEPORTS, OF CANTON, OHIO.

METHOD OF FORGING SIX-THROW CRANK SHAFTS AND DIES THEREFOR.

Application filed October 13, 1922. Serial No. 594,278.

To all whom it may concern:

Be it known that I, HARRY H. KEEPORTS, a citizen of the United States, residing at Canton, county of Stark, State of Ohio, have invented certain new and useful Improvements in Methods of Forging Six-Throw Crank Shafts and Dies Therefor, of which the following is a specification.

This invention relates to an improved method of forging six-throw crank-shafts for automobile engines or similar purpose and the dies therefor.

The object of the invention is to improve such method of forging and avoid undue stretching and straining of the metal and minimize torsional strains of the forging operation.

Objects pertaining to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Fig. I is a side elevation view of a bar that has been submitted to the first step in an edger die in my forging operation.

Fig. II is a plan view of the structure of Fig. I.

Fig. III is an elevation view of the bar after it has been submitted to the second edger die forging operation.

Fig. IV is a plan view of the structure of Fig. III.

Fig. V is a plan view of the completed shaft after the final die operation.

Fig. VI is an elevation view of the completed shaft.

Fig. VII is a cross sectional view taken on line 7-7 of Fig. V.

Fig. VIII is a detail sectional view taken on irregular line 8-8 of Fig. V.

Fig. IX is a detail sectional view taken on irregular line 9-9 of Fig. VI.

Fig. X is a detail sectional view taken on line 10-10 of Fig. V.

Fig. XI is an inverted plan view of the top die member with the corresponding depressions therein.

Fig. XII is a detail plan view of the bot-

tom die showing the three successive sets of die depressions therein.

Fig. XIII is a detail longitudinal sectional view through the superposed die depressions in the first edger, showing the billet in position in the first step of my process.

Fig. XIV is a similar longitudinal sectional view through the second edger die depressions showing the action of the dies in the second step of my process.

In the drawing the sectional views are taken looking in the direction of the little arrows at the ends of the section lines and similar numerals of reference refer to similar parts throughout the several views.

The various parts of the drawing will be identified by their reference numerals. 1 is the billet bar to be handled by its shank 76 2. It is placed first in the first edger die and the central part deflected up as at 3 (see Fig. I) which results in the bar being somewhat flattened at that point, as shown in Fig. II. In the second step the deflected 60 part 3 is turned to horizontal position; that is, the bar is turned one quarter over, and the second edger die is brought into action, forming roughly double throws 4 and 5, and 6 and 7 at each end of the bar, as clearly 65 appears in side elevation in Fig. III. The metal is flattened down to the general contour of the plan appearing in Fig. IV.

The bar is then subjected to the third operation between the complete forming dies, the upwardly deflected portion being placed on the upwardly projecting central portion of the die and the end portions being forced down by a forging and slight bending action until the crank pins are 70 formed in opposite relation, as seen in plan in Fig. V and in elevation in Fig. VI.

There is a single crank arm 8 and 9 at opposite ends, and single central crank arms 10 and 11, and 12 and 13 at each side of 100 the intermediate crank bearings. There are double crank throw arms 14 and 15 connecting the first and second crank pins and the fifth and sixth crank pins at each end, the same having deflected and curved forms, 105 as seen in cross section in Fig. VII.

After the final forming of the crank, of course, the fins should be removed by suitable cutter dies, which is a mere incident of all such operations. The flange head 16 is 110 formed in the usual way and I have not described it in detail.

I make use of forming and forging dies in this behalf. 17 is the bottom die and 18 the top die. I form an edger depression 19 at one edge, which appears in longitudinal section in Fig. XIII. A second edger die 20 is formed where the billet is turned a quarter over. The general contour of this part appears in elevation in Fig. XIV.

There is a final depression die in which 10 the complete contour of the six throw crank shaft is formed. The central cranks are in a vertical central plane and the end cranks are deflected laterally 120° therefrom at each side, as definitely appears on the face of 15 said upper and lower dies illustrated in Figs. XI and XII. The three die impressions can be in separate blocks or combined in blocks to suit individual manufacturing conditions, and can be used as described or reversed.

It will be seen from these steps that the end cranks are deflected downwardly and the double throw cranks 14 and 15 are only slightly bent, as indicated in Fig. VIII, to 25 accomplish the complete formation of the six throw crank shaft. The metal is only stretched to the extent that it would ordinarily be stretched in forming a single crank, and the torsion is substantially negligible, 30 although the crank shaft is being acted upon from end to end by the final dies at the same moment.

The deflecting of the center of the billet could be done as the second operation with 35 the formation of the end crank throws as the first, but the operation would be far less convenient and satisfactory, as it is much easier to handle the straight bar while the center is being deflected than to properly 40 manipulate and place it with the end cranks formed in the rough. I mention this as a possible change in procedure, without departing from the broad principles of the working relation between the steps of manu- 45 facture of my invention. However, I desire

to claim the invention in its approved form specifically as I have described, and also broadly, as pointed out in the appended claims.

Having thus described my invention what 50 I claim as new and desire to secure by Letters Patent is:

1. The process of forming a six throw crank shaft consisting in, first, deflecting to one side the central portion for the central 55 pair of crank pins and arms, second, forming the first and second and the fifth and sixth crank pins and arms at each end at right angles thereto, with a connecting crank between the first and second and the fifth 60 and sixth pins, and third, subjecting the same to a forging action in which the central crank pins are roughly completed and the end two crank pins and arms are deflected from the right angle plane to an 65 angle of 120 degrees and completely rough formed, as specified.

2. The process of forming a six throw crank shaft consisting in deflecting the central part to form the central pair of crank pins and arms, and forming the first and second and fifth and sixth crank pins and arms at right angles thereto, and thereafter subjecting the same to a forging operation 70 in dies conformed to the form of the crank 75 whereby the end crank pins and arms are deflected to position.

3. A series of dies for forming a crank shaft, one of which is formed with a central depression to deflect the center crank 80 throws, another of which is conformed to produce crank throws at the ends of the shaft at right angles to the first deflected portion, and a final forming die with a vertical central portion to conform the central 85 crank throw and deflected lateral portions to form the end crank throws, as specified.

In witness whereof, I have hereunto set my hand and seal.

HARRY H. KEEPORTS. [L.S.]
